[57] CLAIM

The ornamental design for a case for printing calculator or the like, substantially as shown.

DESCRIPTION

FIG. 1 is a left perspective view of a case for printing calculator or the like showing my new design;

FIG. 2 is a top plan view thereof;

FIG. 3 is a front elevational view thereof;

FIG. 4 is a bottom elevational view thereof;

FIG. 5 is a right side elevational view thereof, the left side elevational view being essentially a mirror image thereof;

FIG. 6 is a rear elevational view thereof.
